Primary Examiner—James M. Gandy*Attorney, Agent, or Firm*—Sughrue, Mion, Zinn, Macpeak & Seas[57] **CLAIM**

The ornamental design for an automobile tire, as shown and described.

DESCRIPTION

FIG. 1 is a perspective view of an automobile tire showing our new design, it being understood that the tread pattern is repeated uniformly throughout the circumference of the tire; FIG. 2 is a front elevation view thereof, a rear elevation view, a top plan view, and a bottom plan view are identical with the front elevation view;

FIG. 3 is a left side elevation view thereof, a right side elevation view is identical with the left side elevation view; FIG. 4 is an enlarged fragmentary front elevation view thereof; and,

FIG. 5 is an enlarged cross-sectional view thereof taken along line 5—5 in FIG. 4.
